INVENTOR

BY *Victor J. Evans*

ATTORNEY

WITNESS:

John J. Donovan

UNITED STATES PATENT OFFICE.

OTHO C. ANDERSON, OF WEST NASHVILLE, TENNESSEE.

TRUCK FRAME.

Application filed October 17, 1924. Serial No. 744,246.

To all whom it may concern:

Be it known that I, OTHO C. ANDERSON, a citizen of the United States, residing at West Nashville, in the county of Davidson 5 and State of Tennessee, have invented new and useful Improvements in Truck Frames, of which the following is a specification.

This invention relates to car trucks and 10 contemplates a structure by means of which the bolster or springs can be conveniently and quickly removed for the purpose of repair as the occasion may require, the invention residing in the construction, combination and arrangement of parts as claimed.

15 In the drawings forming part of this application like numerals of reference indicate similar parts in the several views, and wherein:

Figure 1 is a view in elevation of the 20 car truck constructed in accordance with the present invention.

Figure 2 is a sectional view taken on line 2—2 of Figure 1.

Referring to the drawings in detail, 10 25 represents an arched shaped bar upon which the frame 11 of the truck reposes, the frame being of the ordinary well known construction, and including the U-shaped portion for the reception of the bolster 12. The bolster 30 is supported by the usual springs 13, the springs resting on a plate 14 which is seated on the lower end of the U-shaped portion 15 of the frame as shown in Figure 1. Prior to the arrangement of the parts in the manner just described, angle iron bars 16 are 35 arranged in the U-shaped portions, and riveted or otherwise suitably secured thereto as at 17. A wear plate 18 is also arranged between the upper ends of the springs 13 and the bolster 12 as shown in Figure 2. Now, the open end of the U-shaped portion 40 15 is closed by a bridge bar 19 which has its ends reposing on shoulders 20 formed on

the frame, the bridge bar being secured to said frame by means of bolts or other fastening elements 21. By reason of this construction, the parts can be easily removed from the frame for repair, or for any other purpose, with a consequent saving of time and labor. Instead of initially jacking up the 45 bolster to remove the springs and then lowering the bolster down to the bottom of the frame so that it can be taken out, it is only necessary to remove the bolts 21 and then 50 separate the bridge bar 19 from the frame, 55 whereupon the bolster can be easily removed as also the springs or any other part to be repaired.

While it is believed that from the foregoing description, the nature and advantages 60 of the invention will be readily apparent, I desire to have it understood that I do not limit myself to what is herein shown and described, and that such changes may be resorted to when desired as fall within the 65 scope of what is claimed.

Having thus described the invention, I claim:

A car truck frame having a U-shaped portion open at its upper end and adapted to receive the bolster and supporting spring therefore, angle iron bars arranged in the U-shaped portion beneath and parallel with said bolster, a wear plate interposed between the upper end of the springs and said 70 bolster, a wear plate interposed between the lower end of the springs and said angle bars, a bridge bar closing the upper end of the U-shaped portion of the frame and lying substantially flush with the upper surface 75 thereof, and bolts passed through said bar and frame, whereby the former is detachably connected to the frame as and for the purpose specified.

In testimony whereof I affix my signature.
OTHO C. ANDERSON,
